UNITED STATES PATENT OFFICE

98,109

DESIGN FOR A TEXTILE FABRIC

Oscar J. Cahn, New York, N. Y.

Application September 16, 1935, Serial No. 58,566

Term of patent 3½ years

To all whom it may concern:

Be it known that I, Oscar J. Cahn, a citizen of the United States, residing at 2 Park Avenue, Borough of Manhattan, city, county, and State of New York, have invented a new, original, and ornamental Design for a Textile Fabric, for which the following is a specification, reference being had to the accompanying drawing, forming part thereof.

The figure is a plan view of a textile fabric showing my new design, the fabric being provided with superimposed arrangements of fringes, interwoven with the basic fabric in regular pattern.

I claim:

The ornamental design for a textile fabric substantially as shown and described.

OSCAR J. CAHN.
